PIVOTED FLOATING ARTICLE CATCHING
ATTACHMENT FOR SCRUB PAILS

Andrew H. Hatchette, Cleveland, Ohio

Application October 26, 1945, Serial No. 624,864

2 Claims. (Cl. 15—264)

1

This invention relates to an attachment designed for use in connection with scrub pails, the primary object of the invention being to provide a means for catching and holding the scrub cloth, soap or the like within a scrub pail, while the dirty water in the pail is being poured therefrom.

An important object of the invention is to provide a device of this character embodying a plurality of pivoted hooks constructed in such a way that they will swing outwardly to their active positions, the hooks lying on the surface of the water, when the water is being poured from the pail, to catch articles which would otherwise leave the pail with the water.

Still another object of the invention is to provide pivoted hooks which, when the pail is being used in scrubbing, will swing downwardly to a position where the pointed ends of the hooks will rest against the inner surface of the pail to guard against the person using the pail, injuring his hands while holding or placing the scrub cloth or soap in the pail.

With the foregoing and other objects in view which will appear as the description proceeds, the invention consists of certain novel details of construction and combinations of parts, herein-after more fully described and pointed out in the claims, it being understood that changes may be made in the construction and arrangement of parts without departing from the spirit of the invention as claimed.

Referring to the drawings:

Figure 1 is a fragmental plan view of a pail equipped with a device constructed in accordance with the invention, the hooks of the attachment being shown in operative position with the pail full of water.

Figure 2 is a vertical sectional view through the pail illustrating the attachment in elevation.

Figure 3 is a sectional view taken on line 3—3 of Figure 2.

Figure 4 is a fragmental plan view of a pail equipped with a modified form of the invention, the hook of the attachment being shown in operative position with the pail full of water.

Figure 5 is a vertical sectional view through the pail illustrating the modified form of the invention in elevation.

Figure 6 is a view taken on line 6—6 of Figure 5.

Referring to the drawings in detail, the reference character 5 designates a scrub pail, to which the attachment, forming the subject matter of the present invention, is secured.

The attachment comprises an elongated plate 6 curved to conform to the curvature of the pail,

the plate having enlargements 7 at its ends which are formed with openings to receive the rivets 8 by means of which the plate is secured within the pail.

5 The plate is also formed with a plurality of tubular bearings 9 spaced apart to accommodate the tubular portions 10 of the hooks 11, the bearings 9 and tubular portions 10 aligning to accommodate the pivot pin 12 which is shown as 10 extending therethrough.

Each of these hooks comprises a substantially wide portion formed with an opening to accommodate the cork plug 12', the hooks or pointed portions 13 thereof overlying the cork plugs in 15 spaced relation therewith, as clearly shown in Figure 3 of the drawings.

In the form of the invention as shown by Figs. 4, 5 and 6 of the drawings, the attachment comprises a body portion 14 which is secured to the 20 inner surface of the pail by means of the rivets 15, the body portion being disposed adjacent to the mouth or upper edge of the pail.

The body portion 14 is formed with a cut-out portion extending inwardly from one edge thereof, the metal at opposite sides of the cut-out portion providing fingers 16 that have their extremities pointed, providing hooks 17 which extend downwardly in spaced relation with the body portion.

30 The body portion is formed with bearings 18 that register with the tubular portion 19 of the plate 20, for the reception of the pivot pin 20', whereby the plate 20 is pivotally supported with respect to the body portion 14.

35 The plate 20 is formed with a circular opening in which the cork plug 22 is positioned, the free end of the plate being tapered and formed into a hook 23 that overlies the cork plug 22, in spaced relation therewith.

40 It might be stated that in each case, the attachment is arranged at a point at substantially right angles with respect to the bail of the pail, so that in pouring the water from the pail, the water will necessarily be directed over the attachment to the end that a scrub cloth, soap or scrub brush contained in the water will be caught by the hooks and held against passing from the pail with the water.

45 By this device all possibility of the cloth and soap being deposited in the sewage system to clog the system, will be eliminated.

What is claimed is:

50 1. In an attachment for scrub pails, a plate secured to the inner surface of the pail adjacent to the mouth thereof, a pivoted member mounted

on the plate, a hook extending from the free end of the pivoted member, said pivoted member normally lying in a position with the hook resting against the inner surface of the pail, a water buoyant float secured to the hook adapted to float the pivoted member and hook on the surface of the water being poured from the pail, exposing the hook to catch articles poured from the pail with the water.

2. In an attachment for scrub pails, a plate 10 secured to the inner surface of the pail adjacent to the mouth, a pivoted member mounted on the plate, a hook formed on the pivoted member disposed towards the plate, said pivoted member adapted to swing downwardly by gravity, the hook lying against the pail, and a water buoyant float secured to the pivoted member adapted to

5 float the pivoted member on the surface of the water being poured from the pail, exposing the hook in the path of the flow of water from the pail, whereby articles floating on the water being poured from the pail, will be caught by the hook.

ANDREW H. HATCHETTE.
